UNITED STATES PATENT OFFICE.

FRANCIS M. BRINCKERHOFF, OF ENGLEWOOD, AND LEWIS B. STILLWELL, OF LAKEWOOD, NEW JERSEY, ASSIGNEES TO SAID STILLWELL AND HENRY S. PUTNAM, OF NEW YORK, N. Y.

RAILWAY-CAR CONSTRUCTION.

1,231,236.

Specification of Letters Patent. Patented June 26, 1917.

Application filed August 20, 1914, Serial No. 857,660. Renewed May 23, 1917. Serial No. 170,565.

To all whom it may concern:

Be it known that we, FRANCIS M. BRINCKERHOFF, a citizen of the United States, residing at Englewood, in the county of Bergen and State of New Jersey, and LEWIS B. STILLWELL, a citizen of the United States, residing at Lakewood, in the county of Ocean and State of New Jersey, have invented certain new and useful Improvements in Railway-Car Construction, of which the following is a specification.

Our invention relates broadly and generally to new and useful improvements in railway car construction, the primary object being to construct a car which will be extremely rigid in construction, and which will be braced both longitudinally and transversely so that in case of impact, due to collision or other cause, the walls will be sustained against collapse.

A further object is to provide a car structure with a longitudinal member located in, or forming part of, the roof structure for bracing the end portions of the car to oppose collapsing of the ends inward in case of collision, derailment or other impact.

A further object is to construct a longitudinal member for the purpose stated, which may be made up or composed of the elements or parts constituting the roof structure of the car.

A further object is to provide a bracing structure which will support the car roof against collapse in case of overturning and rolling of the car. Other objects will appear in the course of the detailed description of the embodiments of the invention to be given hereinafter.

The invention consists in the improvements to be more fully described hereinafter and the novelty of which will be particularly pointed out and distinctly claimed.

We have fully and clearly illustrated our invention in the accompanying drawings to be taken as a part of this case, and wherein—

Figure 1 is a view in longitudinal section of a car body including our invention in its construction.

Fig. 2 is a detailed perspective view of the roof and deck structure constructed to constitute a preferred form of bracing mem-

ber adapted to resist collapse of the ends of the car.

Fig. 3 is a transverse vertical section on the lines 3—3 of Figs. 1 and 4.

Fig. 4 is a detailed longitudinal central section through a portion of the car body shown in Fig. 1, and on the line 4—4 of Fig. 3.

Fig. 5 is a detailed vertical section on the line 5—5 of Fig. 4.

Fig. 6 is a detailed vertical section through a portion of the car body and the shock-resisting member, the construction of the latter being slightly modified in detail from that shown in Figs. 2, 3 and 5.

Fig. 7 is a detailed sectional view taken on the line 7—7 of Fig. 3.

Fig. 8 is a vertical section through a portion of a car body and showing another form of the shock-resisting member, and

Fig. 9 is a section on the line 9—9 of Fig. 8.

Before proceeding with a detailed description of the preferred embodiment of our invention, we desire to state that the same is not limited to any particular type of car as regards the structure thereof, or the material of which it is constructed, as it is applicable to cars of different types, which may be constructed of wood or metal, or constructed in part of wood and in part of metal, but we have shown and described it hereinafter as being applied to a car constructed of sheet metal of the pressed unit panel side truss passenger coach type forming the subject-matter of United States Letters Patent No. 909,844, dated January 12, 1909, granted to Francis M. Brinckerhoff.

Referring to the drawings by characters of reference, and particularly Fig. 3, 1 designates the underframing of a car, which underframing may be of any suitable construction, but preferably consisting of the center sills 2, having attached thereto cross-bearers 3, supporting a floor 4, the outer ends of said cross-bearers 3 being connected to the side sills 5. 6 designates the unit panel side truss frames forming the sides of the car and the window openings 7, said side truss frames being preferably attached to vertical side posts 8, attached to the side sills 5, and the upper ends of which are con-

nected by pressed steel carlines 9 in arch form, all as clearly shown in Figs. 3 to 7 inclusive of the drawings. The posts 8 may each consist of U-shaped members, the flanges 8^a of which are directed inward toward each other, for a purpose to be set forth hereinafter.

Extending over the carlines 9 is the roof sheathing 10 completing the roof covering. The end walls of the car are indicated at 11, being riveted to the body corner parts, and 12 designates the platform inclosures or vestibules, having the usual ingress and egress doors for the passengers.

The car body end structures are preferably, although not necessarily, of a double bulkhead type, formed by the end wall structure 11 of the car, dividing the car body from the platform inclosure, and by an intermediate structure in the form of a transverse partition or wall 13, spaced apart a suitable distance, say approximately six feet from the wall 11, said walls 11 and 13 forming if desired a saloon accommodation space for any desired purpose. This car body end structure is preferably constructed with four vertical posts 14, supported on the underframing of the car, two of such posts being at each side of the car. If desired the posts at the extreme ends of the car body may consist of the usual body corner posts 8, and the two intermediate posts may be additional posts, or may be two of the side posts 8 heretofore described. These posts 14 may be connected, as by suitable rivets, to the end and side walls of the car. Lying over the upper ends of these posts is a plate 15, preferably disposed in a horizontal plane and which plate may constitute the ceiling of the bulkhead space, said plate being connected to the posts by any suitable means, for instance, angle irons 15^a, said angle irons 15^a engaging said posts and plate and being riveted thereto. The side and front edges of this plate 15 are preferably riveted to the side and end walls of the car respectively, as at 16, the side walls having flanges 17 to which said plates are riveted. This plate 15 is preferably made heavy and rigid enough to maintain the bulkhead structure, intact under collision impacts and tie the side walls of the car together to prevent spreading of the same, in case of collision, as the bulkhead structure will prevent separation of the walls of one car sufficiently to permit the end of another car to be telescoped therein. The plate 15 may be braced by two pairs of columns 18 located at the end wall 11, and the intermediate wall 13, respectively, said posts being supported on the underframe and having their upper ends riveted to said plate. These columns may, if desired, serve as door posts to define the passageways or doorways 19 through the end

wall of the car and the inner bulkhead and leading from the platform to the interior of the car.

Over the carlines covering the bulkhead space the roof sheathing is preferably made heavier or reinforced as shown at 20, see Fig. 1, and the side edges are connected to the upper edges of the side walls of the car, as at 21, so that a rigid structure is provided. The upper or roof portion of the car body end structure is closed preferably at its ends by vertical heads or plates 22, which brace the structure against collapse in case of overturning of the car.

The car body end structure just described is not our joint invention, but is the sole invention of Francis M. Brinckerhoff, and is made the subject-matter of a separate application filed under even date herewith, Ser. No. 857,619.

We do not desire to be limited to the detailed construction of any of the car body end structures just described, as it may be varied without departing from the spirit and scope of our invention, as the latter contemplates other types of car body end structures than that described.

We will now describe the longitudinal shock-resisting member for resisting impact on the end walls of the car, to prevent collapse of said end walls under collision impact, referring particularly to Figs. 2 and 3 of the drawings. Extending from the upper end of each of the side posts 8, heretofore described, is a connecting plate or gusset 23, riveted at its lower end to a flange of the side post 8, as at 24, and having its upper end riveted, as at 25, to the adjacent carline at a point adjacent the juncture of the side walls of the car with the lower edge portion of the roof sheathing. Extending lengthwise of the car and parallel with the side walls of the latter, at points beneath the carlines and preferably, although not necessarily, in the same horizontal plane with the line of juncture between the side walls and the roof, are longitudinally extending beams or sills 26, preferably consisting of L-shaped angle irons, each having a horizontally disposed flange 27 and a vertically disposed flange 28. These sills 26 are preferably connected to the carlines by means of flanged posts or stanchions 29, the lower ends of which posts are riveted to the vertical flanges of the deck sills, as at 30, while the upper ends thereof are riveted to the side flanges of the carlines, as at 31. Connecting the carlines at points adjacent the upper ends of the side posts or stanchions 29 are flanged tie members or stiffeners 32, preferably U-shaped in cross-section, see Fig. 2, and so disposed that one of the side flanges or legs 33 thereof runs parallel with the roof sheathing and is riveted thereto, as at 34. These tie members may be

fastened at their ends to the sides of the carlines by means of angle clips 34^a, which are riveted to the adjacent side faces of the carlines, and to said tie members, as shown 5 in Fig. 2. The lower horizontal flange 27 of each deck sill is connected preferably to the side wall of the car by means of L-shaped cross-bars or stiffener members 35, the ends of which are riveted respectively to 10 said horizontal flange 27 of the deck sill, and to the side faces of the gusset pieces 23, heretofore described, as at 36, 37, respectively. The ends of the sills 26 are preferably connected to the said plates 15 by being carried up over the surface of said plate, as at 26^a, the lower horizontal flanges of said sills being riveted to the plate, as at 15^a. Other means may be employed for connecting the sills to the plate 15.

20 Extending lengthwise of the car are vertical plates 38, the upper horizontal edges of which are riveted, as shown at 39, to the inner flanges 40 of the tie members 32, while the lower edges of said plates are riveted 25 respectively to the vertical flanges 28 of the deck sill 26, said plates 38 being also riveted, as at 41, to the vertical side flanges of the stanchions or posts 29. Running longitudinally of the car and beneath the cross-30 pieces 35 is a horizontal plate 42, said plate being riveted, as at 43, to the horizontal flanges 44 of said cross-pieces 35. It will be seen that the structure just described provides a longitudinally extending beam 35 or member extending from end to end of the car and adapted to resist impact on the end walls of the car, said beam or member being in box-girder form and composed of the roof sheathing, the plate 38 and the 40 plate 42 with their internal bracing members 29, 35, and the inclosed portions of the carlines as well as the deck sills 26, and longitudinally extending tie members 32. The upper longitudinal flanges 17 of the side 45 walls serve as longitudinal connecting members for the girder members at the roof line of the car at the upper edges of the side walls.

In Fig. 6 we have shown a slightly modified form of the invention, in which the cross-pieces 35 are connected directly to the carlines at the juncture of the roof and side walls, instead of to a gusset, as shown in Figs. 2, 3 and 5, and the opposite ends of 55 said cross-pieces 35 are connected to the lower ends of the vertical posts 29, said posts 29 and cross-members 35 being connected by longitudinally extending angle irons 45 corresponding to the sills 26 here-60 tofore described. In this form of the invention an additional longitudinally extending angle iron 46 may be provided to tie the members 29 together at their extreme lower end portions, and for rivet connection with the plate 15, as at 47. The lower

edge of the vertical plate 38 is connected to the vertical member of said tie member 46, as at 48, while the upper end of said plate 38 is connected to the carlines by an angle iron or strip 49 running lengthwise 70 of the car, and the flanges of which are respectively riveted to the upper edge of said plate and to the under faces of the carlines. In this form of the invention the horizontal plates 15 may be secured to the 75 horizontal flanges of the cross-members or stiffeners 35, and are also connected to the side walls of the car by means of angle irons or brackets 50, the respective webs or flanges of which are riveted to said plate 80 15 and the side wall of the car respectively, as shown at 51 and 52.

It will be understood that the strip 49 may be employed as a substitute for the strips 32, or may be used as an additional 85 connecting means for the carlines.

In both embodiments of the invention just described the ends of the horizontal plates 42 preferably abut the innermost transverse edges of the plates 15, so that the box-90 girders will properly resist any inward movement of the car body end structure, as clearly shown in Fig. 4. The plates 15 and 42 preferably abut at a point adjacent the lower edge of the heads or plates 22, at 95 which point one of the stiffeners 35 is riveted, not only to the said plate 42 but also to the plate 22, as shown in Fig. 4. Angle irons or stiffeners 53 may be provided on the opposite side of the head or plate 22 and 100 riveted to the said plate 22 and the adjacent edge portion of the plate 15. By the construction described, impact or thrust exerted on the end structure of the car will be resisted by the girders. In the form of 105 the invention shown in Fig. 6, the ends of the sills 26 may be connected to the plates 15, in the same manner as described with reference to Figs. 2, 3 and 4.

In Fig. 8 we have shown another form 110 of the shock resisting member, in which the car is provided with a raised vertical deck. In this form of the invention the side posts 54 are provided with overhanging carlines 55 formed integral therewith and supporting 115 at their upper ends a longitudinally extending shock-resisting girder 56 riveted to the ends of the carlines, as at 57, and at its upper longitudinal edge supporting the transom or ventilator structure 58, said 120 structure including an upper horizontal structural iron member 59, to which the roof supporting members 60 are riveted, as at 61. The roof sheathing 62 is laid over the carlines 55 and extends upward vertically 125 from the base of the shock-resisting member to a point adjacent the structural iron member 59, at which point it is riveted, as at 63, to the roof sheathing 64 covering the transverse roof supporting members 130

60. In this form of the invention the structural iron member 56 may take a number of different forms, but we prefer to employ a channel iron having the web 65 and flanges 66 extending at right angles thereto. In this form of the invention the shock-resisting member may be connected to the plate 15 by being laid on top thereof and having the lower flange 66 of said member riveted to the plate, as shown in detail in Fig. 9. Said member may be secured additionally to the plate by means of an angle iron 67 laid on top of said plate and having its members riveted respectively to the 15 plate and said member. One or more transverse stiffeners 68 may be employed to bridge the space between the members 56, and to be riveted to the transverse edge portion of the member 15 to brace, and add 20 rigidity to the structure.

What we claim and desire to secure by Letters Patent of the United States is—

1. A car structure comprising a floor, side walls, end walls, a roof structure including 25 roof sheathing, angularly disposed members beneath the roof structure, said members being connected to each other and to the roof structure and to a side wall and constituting a girder member extending longitudinally of 30 the car at the roof portion, said girder member being coöperable with the end walls to resist collapse of said end walls.

2. In a car structure, a floor, end walls, side walls, and a roof structure including 35 carlines, and a roof sheathing, vertically and horizontally disposed plates beneath the carlines, said plates being connected to each other along one edge and at their other edges to the roof structure, and a side wall respectively, said plates and roof sheathing forming 40 a girder extending longitudinally of the car and coöperating with the end walls to resist impact shocks on said end walls.

3. A car structure comprising a floor, side 45 walls, end walls, a roof structure including roof sheathing and a deck structure, and a hollow member extending longitudinally of the car at the roof portion and adapted to resist collapse of the end walls, the wall of 50 said member being composed in part of the roof sheathing and the deck structure.

4. A car structure comprising a floor, side walls, end walls, a roof structure including 55 roof sheathing, a deck structure composed of angularly disposed web members, and a member extending longitudinally of the car at the roof portion and coöperable with the end walls to resist collapse of the said end walls, said member including the roof 60 sheathing and the angularly disposed web members of the deck structure.

5. A car structure comprising a floor, side 65 walls, end walls, a roof structure including roof sheathing and a deck structure composed of vertical and longitudinal web mem-

bers, and a member extending longitudinally of the car at the roof portion and coöperable with the end walls to resist collapse of the said end walls, said member including the roof sheathing, and the said vertical and horizontal web members of the deck structure.

6. A car structure comprising a floor, side 70 walls, end walls, a roof structure including a deck structure, and a member extending longitudinally of the car at the roof portion and coöperable with the end walls to resist collapse of the end walls, said member constituting part of the deck structure.

7. A car structure comprising a floor, side 75 walls and end walls, carlines, a roof sheathing covering the carlines, an element extending longitudinally of the car and located beneath the carlines and parallel to a side wall, and web members disposed at angles 80 to each other and connected to the said element and carlines, and to said element and the side wall respectively, said sheathing, element and web members constituting a box-girder structure adapted to resist 85 collapse of the end walls of the car.

8. A car structure comprising a floor, side 90 walls and end walls, carlines, a roof sheathing covering the carlines, an element extending longitudinally of the car and located beneath the carlines and parallel to a side wall, stiffeners connecting said element with the carlines above said element and to the side wall, and web members extending longitudinally of the car and rigidly connected 100 to said stiffeners, said sheathing, element, stiffeners and web members constituting a box-girder structure adapted to resist collapse of the end walls of the car.

9. A car structure comprising a floor, side 105 walls and end walls, carlines, a roof sheathing covering the carlines, an element extending longitudinally of the car and located beneath the carlines and parallel to a side wall, web members disposed at angles to 110 each other and connected to the said element and the carlines, and to said element and the side wall respectively, and stiffening means for said web members.

10. A car structure comprising a floor, side 115 walls, end walls, a roof structure, and a triangular box-girder extending longitudinally of the car at the roof portion, and adapted to resist collapse of the end walls.

11. A car structure comprising a floor, side 120 walls, end walls, a roof structure, and a triangular box-girder extending longitudinally of the car at the roof portion, and adapted to resist collapse of the end walls, one wall of said box-girder being formed by 125 said roof sheathing.

12. A car structure comprising a floor, side 130 walls, end walls, a roof structure and roof sheathing, and a box-girder extending longitudinally of the car at the roof portion,

and adapted to resist collapse of the end walls, said box-girder being substantially triangular in cross-section and one wall thereof being formed by said roof sheathing, 5 and the other walls by web members extending lengthwise of the car.

In testimony whereof we have hereunto

signed our names in the presence of two subscribing witnesses.

FRANCIS M. BRINCKERHOFF.
LEWIS B. STILLWELL.

Witnesses:

HAROLD E. LOMBARD,

It is hereby certified that in Letters Patent No. 1,231,236, granted June 26, 1917, upon the application of Francis M. Brinckerhoff, of Englewood, and Lewis B. Stillwell, of Lakewood, New Jersey, for an improvement in "Railway-Car Construction," an error appears in the printed specification requiring correction as follows: Page 4, line 121, claim 11, after the word "structure" insert the words *and roof sheathing*; and that the said Letters Patent should be read with this correction therein that the same may conform to the record of the case in the Patent Office.

Signed and sealed this 21st day of August, A. D., 1917.

[SEAL.]

R. F. WHITEHEAD,

Acting Commissioner of Patents.

Cl. 105—201.
